By *John St. John* A.H.S.

UNITED STATES PATENT OFFICE.

CASTELLARI CESARE, OF MONTREAL, QUEBEC, CANADA.

CIGARETTE-MAKING MACHINE.

Specification of Letters Patent.

Patented Oct. 18, 1921.

1,394,250.

Application filed January 26, 1920. Serial No. 354,022.

To all whom it may concern:

Be it known that I, CASTELLARI CESARE, a subject of the King of Italy, and resident of the city of Montreal, in the Province of Quebec and Dominion of Canada, have invented certain new and useful Improvements in Cigarette-Making Machines, of which the following is a full, clear, and exact description.

10 This invention relates to improvements in cigarette rolling machines, and the object of the invention is to provide a simple, durable and efficient machine, small enough to be carried in the pocket, by means of which 15 a person may quickly and easily roll cigarettes.

The device comprises, broadly speaking, a forming tube composed of two trough-shaped members hingedly connected and a 20 rotating member within the former, adapted to wrap the paper around the tobacco.

25 In the drawings which illustrate the invention—

Figure 1 is a plan view of the device 25 closed.

Fig. 2 is a plan view of the device open.

Fig. 3 is an enlarged end elevation of the 30 device.

Referring more particularly to the drawings, 11 and 12 designate a pair of trough-shaped members whose curvatures are of 35 equal radii, the member 11 having a tangentially projecting extension or lip 13. The opposite edge of the member 11 is hingedly 40 connected to one edge of the member 12, so that the members may be swung into position to form a substantially cylindrical tube, as shown in Figs. 1 and 3, or opened to permit the insertion of paper and tobacco. The member 12 is provided with one or more 45 lugs 14 which limit the opening movement and make the apparatus more easily handled. One end of the member 11 is provided with an extension 15, which is bent to true cylindrical form and which forms a bearing for a revolvably mounted cap 16. A trough-shaped plate 17 is connected at one end to the cap and passes through the cylindrical extension 15, within which it may be rotated 50 by revolving the cap. The curvature of the plate 17 is concentric with the curvature of the trough members 11 and 12 when in their normal relation as clearly shown in Fig. 3,

so that by turning the cap the plate 17 may be rotated within the tube formed by the 55 member.

The operation of the device is extremely simple. The machine is open, as shown in Fig. 2, the plate 17 being in the position shown. The cigarette paper is placed in the 60 member 11 upon the plate 17 and the necessary tobacco distributed uniformly on the length of the paper. The paper is placed with the gummed edge uppermost and lying upon or projecting beyond the lip 13. The 65 member 12 is now folded down to its normal position and thereby folds the paper roughly 70 upon the tobacco and at the same time compresses the tobacco. The tightness of the packing may be regulated by the degree of pressure applied to the member 12 to force it toward the member 11. The cap 16 is now 75 revolved and carries the ungummed edge of the paper around inside the gummed edge. If the gummed edge of the paper has been 80 previously moistened and the cap 16 given one or more complete turns, the cigarette will be revolved on its axis within the device, so that the gummed edge is drawn in and 85 pressed against the paper adjacent the ungummed edge. The member 12 is now raised and the cigarette slipped lengthwise out of the member 11 and out of engagement with the plate 17.

Having thus described my invention, what I claim is—

In a cigarette making machine, a pair of hingedly connected members movable into 90 position to form a tube having a longitudinal opening for the gummed edge of a cigarette paper, one of said members being provided at the hingedly connected portion thereof with stop lugs adapted to limit separation 95 of the members, the other of said members being provided opposite the hingedly connected portion thereof with a projecting lip lying outside of the longitudinal opening 100 and forming a support for the gummed edge of the cigarette paper, and a forming plate movable within said members.

In witness whereof, I have hereunto set my hand.

CASTELLARI CESARE,
